UNITED STATES PATENT OFFICE.

HENRY A. HOUSE, OF BROOKLYN, NEW YORK.

GATE.

Specification of Letters Patent No. 29,696, dated August 21, 1860.

To all whom it may concern:

Be it known that I, HENRY A. HOUSE, of Brooklyn, in the county of Kings and State of New York, have invented a new and Improved Gate; and I do hereby declare that the following is a full, clear, and exact description of the same, reference being had to the accompanying drawing, forming a part of this specification, in which—

10 Figure 1 represents a front elevation of my invention. Fig. 2 is a transverse vertical section of the same, the line α , α' , Fig. 1, indicating the plane of section.

Similar letters of reference indicate corresponding parts in both figures.

This invention consists in arranging a knee or toggle joint and two pendulum levers in combination with two hand levers in such relation to the gate or gates, which are suspended from said pendulum levers that by depressing either one or the other of said hand levers the pendulum levers are forced apart by the action of the toggle joint, and the gates are opened and kept open until 25 the toggle joint is brought within a horizontal line drawn through its center; and this invention consists also in combining with said toggle joint and hand levers two hinged weighted dogs which retain the gates 30 when closed, and which are released by the levers before they act on the toggle joint, thus allowing the gates to open without obstruction when the levers are pulled, but preventing them opening spontaneously or 35 by the force of the wind or from any other cause.

To enable those skilled in the art to fully understand my invention I will proceed to describe its construction and operation with 40 reference to the drawing.

The gates A, A', are suspended from pendulum levers B, B', which are fulcrated in pivots a , in the cross-pieces b , which form the top of the frame C. In order to cause the 45 gates to swing back parallel they may be either provided with an additional support c , consisting of a rope or chain suspended from the outside of the frame C, and connected to the outer edge of the gate A, or 50 they may be furnished with curved guides c' , sliding on pins c'' , in the lower part of the frame C. Such a guide is attached to the gate A', and either of these devices serves to keep the gate in an upright position as it 55 swings back so that it clears snow or other

obstructions which may have accumulated outside the frame C, and that it is always in the proper position to close down readily.

The pendulum levers B, B', are connected by pivots d , d' , to toggle arms D, D', which are united by their fulcrum pin e . By depressing the center of this toggle joint the pendulum levers are forced apart and the gates swing open, as shown in red outlines in Fig. 1. Hand levers E, E', serve to depress the toggle joint and to open the gates, and these levers extend far enough from the gate to enable the driver of a vehicle or a rider on horseback to open the gate conveniently as he approaches the same. Said 65 levers turn on pivots f , f' , in pendants g , g' , which extend from either side of the frame C, as clearly shown in Fig. 2, and they are connected by a cord or wire in such a manner that if one of the levers is depressed the 70 other is raised, and vice versa.

When the gates are open the toggle arms assume a position a little below a horizontal line, so that the gates are kept open until the fulcrum e , of the toggle arms is raised above 80 the line drawn through the pivots d , d' , which connect them to the pendulum levers. This is effected by giving a slight jerk to that one of the levers E, E', which was raised in opening the gate, and the gates are 85 now allowed to close by their own gravity.

When the gate is closed the toggle arms are kept in their places by means of dogs F, F', which are secured to said arms by means of pivots h , h' . Their outer ends are 90 loaded with weights i , i' , and they catch over small cross bars in the upper part of the frame. In order to be able to depress the toggle arms it is necessary to first raise these dogs so as to disengage them from the cross 95 bars j , j' . This is effected by levers E, E', which rest on the inner curved ends of the dogs, the weights i , i' , being sufficiently heavy to counteract the weight of the levers, so that by depressing one or the other of 100 said levers the dogs are first disengaged before the lever acts on the toggle arms. These dogs are intended to keep the gate closed and to prevent its being opened spontaneously.

This gate can be built with little expense and its operation is simple and easily understood, and it will work with equal facility in stormy as in fair weather.

Having thus fully described my invention 110

what I claim as new and desire to secure by Letters Patent is—

1. The arrangement and combination of the toggle arms D, D', hand levers E, E', pendulum levers B, B', and gates A, A', constructed and operating substantially in the manner and for the purpose set forth.
- 5 2. The combination with the toggle arms

D, D', and hand levers E, E', of the weight-ed hinged dogs F, F', arranged substantially as and for the purpose specified.

HENRY A. HOUSE.
